Co. LPA(57) **CLAIM**

An ornamental design for a female hose fitting, as shown and described.

DESCRIPTION

FIG. 1 is a front perspective view of a female hose fitting;
 FIG. 2 is a side view of the female hose fitting;
 FIG. 3 is a front view of the female hose fitting;
 FIG. 4 is a rear view of the female hose fitting; and
 FIG. 5 is a rear perspective view of the female hose fitting;
 and,
 FIG. 6 is a partial cross-sectional view taken along line 6-6
 of FIG. 2.
 The broken lines in the drawings depict portions of the
 female hose fitting that form no part of the claimed design.
